United States Patent Office

Des. 222,933
Patented Feb. 8, 1972

222,933

MOBILE STORAGE CABINET

Hesper P. Brown, 1314 Portland Ave.,
Walla Walla, Wash. 99362

Filed June 26, 1970, Ser. No. 23,679

Term of patent 14 years

Int. Cl. D12—16

U.S. Cl. D14—3

Fig. 1

Fig. 2

FIG. 1 is a rear perspective view of a mobile storage cabinet showing my new design;

FIG. 2 is a front elevational view.

The side opposite to the one shown is the same except for the rectangular receptacles and door on the side.

I claim:

The ornamental design for a mobile storage cabinet, as shown and described.
